ATTORNEYS

UNITED STATES PATENT OFFICE.

CHARLES KILLARS, OF STONINGTON, CONNECTICUT.

LAMP LOCK.

Application filed August 5, 1922. Serial No. 579,921.

To all whom it may concern:

Be it known that I, CHARLES KILLARS, a citizen of the United States, and a resident of Stonington, in the county of New London 5 and State of Connecticut, have invented a new and Improved Lamp Lock, of which the following is a full, clear, and exact description.

This invention relates to improvements in 10 lamp locks, and more particularly to an attachment for lamps of the incandescent type which operates to prevent theft of the lamp, as it securely holds the lamp in the socket against retrograde movement, and can not 15 be removed without destroying the lamp.

A further object is to provide improvements of the character stated, which can be installed at a reasonably low price, which will not interfere with the insertion of the 20 lamp in the socket, but which will absolutely prevent unauthorized removal without damaging the lamp.

With these and other objects in view, the invention consists in certain novel features 25 of construction and combinations, and arrangement of parts, as will be more fully hereinafter described and pointed out in the claims.

In the accompanying drawings— 30 Figure 1 is a view in side elevation showing my improvements in position on the electric lamp.

Figure 2 is a fragmentary view in longitudinal section on the line 2—2, of Figure 1. 35 Figure 3 is a view in transverse section on the line 3—3, of Figure 1.

Figure 4 is a perspective view of the bar 8.

Figure 5 is a perspective view of the 40 spur 7.

1 represents a lamp or bulb of any form and 2 is the screw threaded lamp shell to which the filament terminal 3 is secured and grounded as shown at 4, which is the customary form of construction.

The threaded portion of the shell 2 is provided with a plurality of inwardly offset portions 5, the metal being slit as shown at 6 to permit said offset portions to be 50 formed, and these offset portions constitute a guide for a draw bar 8, the lower end of the latter being preferably provided with an eye 9 to receive a hook or other tool to permit forcible withdrawal thereof.

65 This draw bar 8 is formed with a notch 10 receiving the terminal wire 3 therein so

that the withdrawal of the bar 8 will serve to sever or break the wire 3 and destroy the efficiency of the lamp.

7 represents a sharp end spur, see Fig. 5, 60 which is projected through a slot 11 in the screw threaded portion of shell 2 and is formed with a pair of slits 12 and a laterally offset portion 13 through which a laterally offset tongue 14 on the bar 8 projects, and this coupling of the spur 7 and bar 8 serves to maintain the sharp end of the spur projected from the shell and in position to bite into the socket (not shown) when any attempt is made to unscrew the shell. 70

It is apparent that the shell can be readily screwed into the socket, as the spur will act as a ratchet and not interfere with this operation, but any attempt to unscrew the shell will force the spur into the thin wall of the 75 socket as indicated clearly in Figure 3, and prevent removal of the lamp.

To remove the lamp it is necessary to exert a downward or longitudinal pull on the bar 8 withdrawing the lug 14 from the 80 offset portion 13 of spur 7 and in doing so, the terminal wire 3 will be severed or broken, so that the lamp will be out of commission. When the bar 8 is removed the spur is free to move inwardly and will not 85 interfere with the removal of the lamp.

Various slight changes might be made in the general form and arrangement of parts described without departing from my invention, and hence I do not limit myself to 90 the precise details set forth, but consider myself at liberty to make such changes and alterations as fairly fall within the spirit and scope of the appended claims. 95

I claim:

1. A lock for incandescent lamps, comprising a lamp shell, a transversely positioned sharp spur normally projecting from the wall of the shell, and a longitudinally movable bar having means normally holding the spur in projected position and having means engaging the filament terminal of the lamp to sever said filament when partially withdrawn to release the spur. 100

2. In combination with a lamp, a screw threaded shell on the lamp, a filament terminal fixed to the shell, a sharp spur projecting through the shell, a longitudinally positioned bar coupled to the spur and holding it in projected position, said bar having a notched portion receiving the 105 filament terminal of the lamp whereby a 110

longitudinal pull of the bar to release the spur will operate to sever the ground connection of the filament terminal with the shell.

- 5 3. A lamp, a shell on the lamp, inwardly offset portions in the shell, a bar positioned in said offset portions, a transversely positioned sharpened spur located in the shell and projecting through the same, said spur
10 having a laterally offset portion, a tongue on the bar normally in the offset portion of the spur and holding the latter in projected position, said bar having a notch therein receiving the filament terminal of the lamp
15 whereby a movement of the bar to release the spur will operate to sever the connection between the terminal and the shell.

4. A lamp lock, comprising a lamp shell, a spur projecting through the shell, a spur holding bar longitudinally movable in the shell, and a lamp filament terminal carried by the shell and engaging the bar and severed thereby when the bar is moved to release the spur.

- 20 25 5. A lamp lock, comprising a screw threaded lamp shell, locking means for the shell, said means permitting the shell to be screwed into a socket but preventing it from being unscrewed therefrom, and means slid-
30 ably mounted in the shell and operable from

the exterior of the shell for rendering the locking means operative and inoperative.

6. A lamp lock, comprising a screw threaded shell, locking means for the shell, said means permitting the shell to be 35 screwed into a socket, but preventing it from being unscrewed therefrom, and means slidably mounted in the shell and operable from the exterior of the shell for rendering the locking means operative and 40 simultaneously therewith severing the filament terminal of the lamp.

7. In an incandescent lamp, a shell, means for locking the shell on the lamp and a member movably mounted in the shell and 45 operable from the exterior thereof, said member controlling the locking means and having means for severing the filament terminal of the lamp when operated to render the locking means operative. 50

8. In an incandescent lamp, a shell, means for locking the shell on the lamp, and a bar slidably mounted in the shell and operable from the exterior thereof, said bar controlling the locking means and having a 55 notch for receiving the filament terminal of the lamp, whereby when the bar is partly withdrawn from the shell to release the locking means the filament will be severed.

CHARLES KILLARS.
